UNITED STATES PATENT OFFICE.

NICHOLAS C. THALHEIMER, OF BALTIMORE, MARYLAND, ASSIGNOR OF ONE-THIRD TO
CHARLES A. THALHEIMER, OF BALTIMORE, MARYLAND.

BOLT-RETAINER.

1,034,533.

Specification of Letters Patent. Patented Aug. 6, 1912.

Application filed October 3, 1911. Serial No. 652,548.

To all whom it may concern:

Be it known that I, NICHOLAS C. THALHEIMER, a citizen of the United States, residing at Baltimore, in the State of Maryland, have invented certain new and useful Improvements in Bolt-Retainers, of which the following is a specification.

This invention relates to bolt retaining devices and more particularly to devices of this character for holding the head of a bolt while the nut is being turned or screwed up thereon.

One of the principal objects of the invention is to provide an improvement upon the type of structure illustrated in my copending application, Serial No. 618,884, which was filed Apr. 4, 1911.

A further object of the invention is the provision of a bolt head securing device which may be mounted upon a support and which will permit the insertion of a bolt head therein and its removal therefrom without having access to the head of the bolt.

The device is particularly adapted for attaching the end and side ladders or hand holds to house cars. These ladders or hand holds are compelled to be not more than eight inches from the end of the car, which requirement necessitates the bolts for securing the same being passed through the end posts on some types of cars. In all house cars and particularly refrigerating cars, where the refrigerating tanks are mounted in the end the inner sheathing of the car effectively conceals the bolt and where the tanks are used it is necessary to remove both the tanks and the sheathing to remove the bolts from the posts when they become broken or sheared off through contact with objects along the road.

This invention is designed to obviate the difficulty and necessary expense of removing the tank and the sheathing and provides means whereby the bolt may be inserted from the outside and removed in the same manner, even when sheared off flush with the face of the car.

Further objects of the invention will appear as the following specific description is read in connection with the accompanying drawing which forms a part of this application and, in which:

Figure 1 is a fragmentary side elevation of a box car showing the ladder rungs attached thereto and with one of the rungs

broken away. Fig. 2 is a detail horizontal section taken through the car on a line with the securing bolt and on an enlarged scale. Fig. 3 is a detail section through one of the retaining plates or washers. Fig. 4 is a similar view taken at right angles through Fig. 3. Fig. 5 is a horizontal section on the line 5—5 of Fig. 4. Fig. 6 is a fragmentary perspective section of the bolt.

Referring more particularly to the drawing, 1 represents a corner post or upright to which is secured the inner sheathing 2. The outer portion of the post 1 has secured to it a filler block or post 3 to which is secured the outer sheathing 4 which forms with the inner sheathing an air space 5. Separated a suitable distance from the corner post 1 is another filler block or post 6 which is connected to both the inner and outer sheathing 3 and 4. The corner post 1, the filler post 3 and the filler post 6 are all provided with a vertically aligned series of transverse passages or openings 7 which are substantially oblong in cross section so as to receive and permit the passage of the oblong head 8 of the rung bolt 9 and also to permit the insertion of the thumb and fore finger on opposite sides of the bolt, as will be hereinafter described. These bolts pass through a washer 10 which is seated against the sheathing 4 and has a pair of spaced lugs 11 arranged in the aperture or opening 7 so as to hold the bolt centrally therein. The outer ends of the bolts pass through the rung heads 12 and are held in place by suitable nuts 13.

The bolt mounting or retaining device comprises an integral casting having a base 14 in the form of a plate which is apertured at opposite ends, as shown at 15, to receive securing devices which may be in the form of screws, nails or the like. In the center of the plate a transverse slot or opening 16 is formed and covering the opening is a substantially U-shaped housing 17 having a short side wall 18 upon one side and a similar side wall 19 at the opposite side. These side walls extend from the top of the plate to the top of the housing and from the end walls thereof to the edges of the opening. Immediately opposite the side walls 18 and 19 the base or plate is provided with a pair of cams 20 upon which the head of the bolt is adapted to ride prior to being dropped into the sockets 21 which are

formed by the side walls, the base and shoulders 22 produced by the termination of the cams. The filler upright 6 is provided with a plurality of recesses 23 which register with the openings 7 therein and in which the retaining members are mounted so that the inner sheathing can be arranged flush with the inside of the post and so that the attaching members may be concealed thereby. It will be understood that if found desirable the corner post may also be treated in a like manner.

In the before-mentioned application it was found that the structure shown therein was faulty to the following extent: In practice, when it was desired to remove the bolt the head of the same would catch over the head of the plate at opposite ends of the aperture which made it necessary to move the bolt to locate the aperture. In the present construction cam lugs 24 are arranged at opposite ends of the aperture so that their inner cam faces form the end walls of the aperture and serve to guide the head of the bolt to the aperture, thus facilitating its removal from the mounting member, as will hereinafter be described.

In building up the car the bolt attaching plates or members are first applied to the post 30 and filler upright before the sheathing is put on and the outer sheathing is apertured to correspond with the passages or openings 7. The bolts are then inserted through the passages and through the slots or openings 16 in the 35 attaching members and given a quarter turn so that the head will ride upon the cam 20 and eventually seat their heads in the sockets 21. The washers 10 are then placed upon the bolts and the rungs secured thereagainst 40 upon the bolts by the nuts 13. When the bolt is sheared off in any manner the washer 10 is removed and the fingers inserted in the aperture on opposite sides of the bolt, so that it may be forced inwardly until free of 45 the socket or until it contacts with the top of the housing. It is then given a quarter turn until it comes in contact with the edges of the side walls 18 and 19 when it may be readily withdrawn from the attaching member, the cams 24 guiding the same through 50 the openings 16. A new bolt is then placed in position in the manner before described and the rung or hand hold secured thereon, as will be readily understood.

55 It will be noticed that the passages are of such construction as to permit the fingers to be inserted to grab the bolt even where the same has been sheared off flush with the outer surface of the car. It will also be noticed that it is not necessary to remove any 60 part of the inner or outer sheathing to replace a broken bolt.

Having thus described the invention, what is claimed is:

65 1. In a device of the class described, the

combination with a channeled support, of a bolt passing through said channel and having a head of smaller sectional area than the channel, apertured means to receive and engage said bolt, to prevent the same from turning, means carried by the last-named means for guiding the bolt in its removal therefrom together with an object securing member on the bolt.

2. In a device of the class described, the combination with a channeled support, of a bolt passing through said channel and having a head of smaller sectional area than the channel, apertured means to remove and receive and engage the head of the bolt to prevent the same from turning, guiding members carried by said means on opposite sides of the aperture and adapted to guide the head of the bolt in its removal therefrom and an object securing member on the bolt.

3. In a device of the class described, the combination with a channeled support, of a bolt passing through said channel and having a head of smaller sectional area than the channel, a socket member secured to the support and having an aperture registering with the channel in the support, means to guide the bolt head to the socket in said member and means to guide the bolt head to the aperture in its removal from said member, together with a nut on the bolt.

4. In a device of the class described, the combination with a channeled support, of a bolt passing through said channel and having a head of smaller sectional area than the channel, an apertured housing secured to one side of the support and registering with the channel, means formed upon the housing to prevent the bolt from turning and means to guide the removal of the bolt therefrom.

5. In a device of the class described, the combination with a channeled support, of a bolt passing therethrough and having a head smaller than the sectional area of the channel, a retaining member secured over the channel and having an aperture to connect the passage of the bolt head, said member having sockets therein, means to limit the rotation of the bolt head and to guide the same to the socket, means to prevent the bolt from passing through said member in its entirety and means to guide the removal of the bolt head from the member.

6. In a device of the class described, the combination with a channeled support, of a bolt passing through the channel therein and having a head of smaller sectional area than the channel, a slotted retaining member secured to one side of the support and adapted to removably receive the bolt head, limiting shoulders formed on the member, cams opposite the limiting shoulders and forming therewith sockets to receive the head of the bolt to prevent the same from turning, guid-

ing cams arranged at opposite ends of the slot and adapted to guide the removal of the bolt head from the member, a housing to limit the longitudinal movement of the bolt 5 through the member and a rung securing nut carried by the bolt.

7. In a device of the class described, the combination with a channeled support, of a bolt passing through said channel and having a head of smaller sectional area than the channel, means secured independently of the bolt to the rear of the support for engaging said bolt to prevent the same from turning, together with means to secure an object on 15 the bolt on the front of the support.

8. In a device of the class described, the

combination with a channeled support, of a bolt passing through said channel, and having a head of smaller sectional area than the channel, a slotted housing secured independently of the bolt to one side of the support and adapted to removably receive the bolt, means formed in the housing to prevent the bolt from turning, and a nut for securing an object on the bolt on the opposite side of 20 25 the support.

In testimony whereof I affix my signature in presence of two witnesses.

NICHOLAS C. THALHEIMER.
